Rufus Lapham

United States Patent Office.

RUFUS LAPHAM, OF NEW YORK, N. Y.

Letters Patent No. 71,766, dated December 3, 1867.

INKSTAND.

The Schedule referred to in these Letters Patent and making part of the same.

TO ALL WHOM IT MAY CONCERN:

Be it known that I, RUFUS LAPHAM, of the city, county, and State of New York, have invented certain Improvements in Inkstands; and I do hereby declare that the following is a full and exact description thereof, reference being had to the accompanying drawings, and to the letters of reference marked thereon.

The nature of my invention consists in applying to an inkstand a sponge, or any other suitable absorbing substance, which, being compressed by means of a screw or otherwise, shall discharge the ink as desired, and reabsorb it on the pressure being released.

The accompanying drawing represents an inkstand with improvements, *S* being the sponge, resting upon the bottom of the stand; *d*, a cap or plate, working upon said sponge; *c*, a cover attached to the main vessel by means of screw at *g g*; *a*, a screw passing through said cover, upon the cap or plate *d*; *l l*, lips into which the ink is compressed for use, through a hole leading into the vessel at *e e*. Now, by turning the screw *a* downward, the sponge becomes compressed, and the ink is thrown into the lips as wanted, which also returns again by the absorbing principle of the sponge when the screw is turned upward.

The utility of this improvement in inkstands is readily seen. First, it filters the ink; second, the inkstand becomes portable, although entirely open; third, the ink is held by the even pressure at any desired altitude in the lips, and never rises or falls in any considerable degree by change of temperature, the fatal objection to many other kinds of stands, and being always at the same altitude, the pen will take up an even quantity of ink at every immersion, thereby preventing the frequent blots which appear in writing.

What I claim, and desire to secure by Letters Patent, is—

An inkstand, made substantially as described.

RUFUS LAPHAM.
